Attorney.

UNITED STATES PATENT OFFICE

2,538,693

SHELL LIFTING AND SEALING PLUG

Oliver Maisch, Chicago, Ill.

Application February 1, 1949, Serial No. 74,035

4 Claims. (Cl. 294—93)

1

Great quantities of ammunition in the form of loaded shells are kept in underground storage where the surface finish gradually deteriorates. After being so stored for a considerable length of time, the shells must be refinished before they can be used. These shells commonly have in one end a screw threaded opening into which are screwed lifting devices, by means of which shells may be suspended from carriers for transportation and manipulation. After a shell has been refinished, the lifting device must again be unscrewed. The screwing in and unscrewing of a lifting device takes considerable time and therefore adds very substantially to the labor cost of handling and refinishng the shells.

The primary object of the present invention is to produce a simple and novel lifting device that can be applied to and removed from a shell quickly and easily, thereby substantially decreasing the amount of labor required to perform these operations and making them less expensive.

In carrying out my invention I employ an expandable plug that can be slipped into the screw-threaded opening of a shell and then be expanded quickly into interlocking relation with the surrounding screw threads; the parts that engage with the metal of the shell being of flexible rubber or rubber-like material, which not only creates the desired interlock without marring the screw threads, but also seals the opening into which the device is inserted.

Therefore, viewed in one of its aspects, the present invention may be said to have for an object to produce a simple and novel, threadless, and quickly attachable and detachable plug for sealing a screwthreaded opening in a shell or any other article without marring the screw threads and without requiring that the thread be of some particular type, pitch, or size; the plug being provided with means, if desired, for suspending and carrying the article in which the opening exists.

The simplest way of expanding the plug is to provide it with a camming handle which, after reaching the position necessary for proper expansion of the plug, will remain in that position while being employed to suspend the shell or other article from a hook or other support; thus locking the handle in the position to hold the plug in place until the handle is relieved of the weight of the article.

Consequently, one of the objects of the present invention may be said to be to provide a quickly attachable and detachable expandable sealing

plug for an opening with an operating handle that serves also as a means for suspending the article to which the plug is secured.

The various features of novelty whereby the present invention is characterized will herein-after be pointed out with particularity in the claims, but, for a full understanding of the invention and of its objects and advantages, reference may be had to the following detailed description taken in connection with the accompanying drawing, wherein:

Figure 1 is an axial section through one end of a shell into the screwthreaded opening of which a device embodying the present invention has been inserted, preparatory to being interlocked therewith; Fig. 2 is a section on line 2—2 of Fig. 1, showing the device locked in place; and Fig. 3 is a section on line 3—3 of Fig. 1.

In the drawing I have illustrated my invention as adapted for lifting and sealing an artillery shell and, for the sake of brevity, shall confine the detailed description to this particular use; it being understood that the device is not limited to use only in this particular field, but may be used wherever there may be an advantage in so doing.

In the drawing, A is a fragment of a conventional artillery shell having in one end a large opening provided with internal screw threads B. In the inner end of the opening is fitted a conventional "fuse well cup" C that seals the opening at all times. The specific plug device illustrated comprises a body member 1 of soft rubber having a main cylindrical section 2 provided at one end, the upper or outer end, with a part 3 of greater diameter that constitutes a head. The cylindrical portion is hollow, so that the body member has the shape of an inverted cup, the cylindrical part of which is small enough in diameter freely to enter the opening in the shell, while the laterally protruding part of the head rests on the portion of the shell around and immediately adjacent to the opening; the flange may have an edge portion that is frusto-conical as shown at 4; so that this portion of the body member may be wedged into the opening in the shell if pressed down. Within the part 2 is a stiff metal sleeve 5 somewhat shorter than the depth of the cup, to prevent the cylindrical wall of the cup from being pushed inwardly toward the axis.

Underlying the rubber body member is a thick, rigid metal disc 6 of the same diameter as part 2 of the body member. On top of the body member is a second rigid disc 7 of the same diameter

as the head section 3. An axial stem 8 extends loosely through disc 7 and head 3 of the body member and through and in screwthreaded relation to disc 6; 9 being the screw threads on the lower end of the stem. A lock nut 10 is screwed on the lower end of the stem below and in engagement with the lower disc. The stem terminates in an eye 11 a little above the upper disc. Embracing this eye is a fork 12 on one end of a short handle 14. A pin 15, extending through the two prongs of the fork and the interposed eye, effects a hinge joint between the handle and the stem. The end edges 16 at the free ends of the prongs of the fork are cams which have flattened portions 17 intersected by a plane containing the axes of the handle and hinge pin. The free end of the handle is in the shape of a large eye 18, the plane of which is parallel to the plane just mentioned.

The parts are so proportioned that when the handle is swung down to lie parallel with the top of the upper disc, there is a clearance between the fork portion of the handle and the upper disc, so that there is no pressure on the rubber member. When the handle is swung up, however, the cam sections of the fork approach and finally engage and force down the upper disc. By the time that the handle has swung through an angle of ninety degrees and is thus aligned with the stem, the flat edge portions 17 of the cams rest for their whole lengths on the disc and thus serve to hold the handle so aligned with the stem. During such swinging movement of the handle, the discs are drawn toward each other, compressing the rubber body member; and, since sleeve 5 prevents movement of the rubber toward the center, the cylindrical part increases in external diameter.

In using the device, the handle is set in its idle or release position and the plug is slipped into the opening in the shell, coming to rest when the rubber flange engages the shell. The situation is now that illustrated in Fig. 1. It will be noted that the lower disc 6 is an aid when entering the plug in the opening, because it is not only smooth but is rigid and does not become distorted if it touches the threads in the shell opening. After the plug has been set into the opening, the handle is swung up, as in Fig. 2, the rubber being expanded into the valleys of the threads B and forming an effective interlock. The eye 18 on the handle presents a large area against which the palm of a hand may press forcibly to swing the handle into its upright position. It should also be noted that lower disc 6 serves not only as a guide in entering the plug in the opening and as an anvil on which the rubber body member rests, but keeps the body member centered in the opening and insures even expansion thereof in all radial directions.

The grip of the plug is so great that shells each weighing several hundreds of pounds may be lifted and carried from place to place by supporting this entire weight from the plug.

The expanded plug effectively seals the opening in the shell so that no foreign matter can enter such opening while the plug is interlocked with the shell. If a shell be repainted, for example, no paint can enter the opening with the plug in place. The flange on the body member provides the first sealing line, as it is compressed more or less and forced tightly against the metal edge surrounding the opening in the shell and to some extent against the marginal portion of the outer surface of the shell around the opening, as

shown in Fig. 2. Also, when expanding pressure is applied to the rubber body, the rubber in the head section thereof is pressed tightly against that portion of the stem surrounded thereby, so that an effective seal against outward leakage of fluids along the stem is created.

After the work to be done on the shell is completed, the plug may be removed by simply swinging the handle down and lifting the plug out; the elasticity of the rubber being such that the body member resumes its original shape upon release of the pressure.

It should be noted that although I have shown my device only as applied to a screw threaded opening, it may be used in threadless openings, as well, particularly where the main purpose is to seal an opening. In the construction illustrated, the threads B in effect constitute annular shoulders underneath which the rubber ridges lie when the plug has been expanded into the opening in the shell. Therefore it may be said that the lowermost thread engaged by the rubber seals the inner or lower end of the opening. Thus the principle is the same, in this respect, as when the plug is inserted in an opening or bore of less axial length than the bore, so that the rubber extends down below the lower end of the bore; so that, in expanding, the rubber bulges laterally underneath an annular shoulder that surrounds the lower end of the bore and creates a seal.

While I have illustrated and described with particularity only a single preferred form of my invention, I do not desire to be limited to the exact details thus illustrated and described, but intend to cover all forms and arrangements that come within the definitions of my invention constituting the appended claims.

I claim:

1. A combined sealing and lifting plug comprising a stem, a handle hinged at one end to one end of the stem so as to be movable from a position in alignment with the stem to a second position transverse to the stem, means at the other end of the handle to attach it to a suspending device, an expansible means including a cylindrical body member of soft rubber surrounding and in spaced relation to the stem and rigid plates overlying and underlying the body member, and a nut on the lower end of the stem, and a cam on the hinged end of the handle engaging said plate to force the expanding means down against the lower of said plates and cause the body member to expand laterally when the handle is swung into alignment with the stem and to allow the body member to resume its normal diameter when the handle is swung into its second position.

2. A combined sealing and lifting plug comprising a stem having a nut on one end, a handle hinged at one end to the other end of the stem so as to be movable from a position in alignment with the stem to a second position transverse to the stem, an expansible means including a cylindrical body member of soft rubber in the form of an inverted cup and underlying and overlying rigid discs surrounding the stem and resting on said nut, a rigid sleeve, shorter than the depth of the cup, filling within the cup, and a cam on the hinged end of the handle engaging the nearer disc to force the expanding means down against said nut and cause the body member to expand laterally when the handle is swung into alignment with the stem and to allow the

body member to resume its normal diameter when the handle is swung into its second position.

3. A plug device comprising a rubber body member in the form of an inverted cup, rigid clamping plates arranged one above and the other below said body member, a stem extending loosely through the upper plate and the cup bottom of the body member and extending also through and in screwthreaded relation to the lower plate, a nut on the lower end of the stem engaged with the lower plate to lock it against downward movement on the stem, a cam device on and hinged to the upper end of the stem to force the upper plate down to compress the rubber and cause it to expand laterally, and a part on said cam device that serves as a handle.

4. A plug device comprising a thick body member of flexible rubber in the form of an inverted cup, a sleeve somewhat shorter than the depth of the cup fitted in the cup to prevent the wall of the latter from being deflected inwardly, rigid clamping discs, one above and the other below said body member, a stem extending loosely through the upper disc and the body member and also through and in screwthreaded relation to

10

the lower disc, a nut on the stem below and in engagement with the lower disc, a cam device hinged to the upper end of the stem in position to engage the upper disc and force it down so as to compress the rubber member and cause it to expand laterally, a handle fixed to the cam device in position to be aligned with the stem when the said cam device is in clamping position, and said handle containing an opening to receive an element adapted to suspend the plug device and an object to which the latter is attached.
